UNITED STATES PATENT OFFICE.

SAMUEL J. HORSCH, OF ROCKFORD, ILLINOIS.

HAYRACK.

Application filed May 28, 1921. Serial No. 471,801.

To all whom it may concern:

Be it known that I, SAMUEL J. HORSCH, a citizen of the United States, residing at Rockford, in the county of Winnebago and 5 State of Illinois, have invented certain new and useful Improvements in Hayracks, of which the following is a specification.

This invention relates to hay racks, and the primary object is to provide a generally improved rack structure, especially with regard to the sides and to the means for supporting the same.

I have aimed to construct these supporting means in such novel manner as to allow 15 quick removal thereof, and when in operative position to rigidly and substantially support the sides. I have further aimed to so construct the side supporting means that when the sides are removed there will be no 20 lateral projections from the rack bottom such as would be a source of danger.

Another object is to provide novel means for quickly converting an ordinary flat bottom wagon rack into a hay rack by the 25 addition of supplemental sides.

Still another object of my invention is to provide novel means for supporting the sides of a rack, so constructed that they may be produced at a comparatively low cost 30 and may be sold in sets independent of the rack proper so that they may be readily applied by any farmer.

Further objects and attendant advantages will be appreciated as the invention be- 35 comes better understood by reference to the following description when considered in connection with the accompanying drawings, in which—

Figure 1 is a front view of a hay rack 40 embodying my invention;

Fig. 2, a side view of the rack;

Fig. 3, an enlarged sectional view taken substantially on the line 3—3 of Fig. 2;

Fig. 4, a top view of the lower fastening 45 for one of the braces; and

Figs. 5 and 6, detail sectional views taken substantially on the lines 5—5 and 6—6, respectively, of Fig. 3.

Referring now more particularly to the 50 drawing, the rack bottom may be of any suitable or preferred construction, and in the present instance consists of the usual cross beams 7 upon which the flooring 8 is laid. The usual uprights posts 9 are pro- 55 vided at the front end of the rack.

The sides are made separate from the bot-

tom and likewise may be of any suitable construction. Those shown comprise members 11 joined by horizontal portions 12, it being observed that the boards 12 are attached to the outer sides of the uprights 11. 60

A number of pairs of brackets are now provided for detachably connecting the sides to the rack bottom, these pairs of brackets being applied at the front and 65 back ends of the sides and at one or more intermediate points. Each pair consists of a bracket 13 in the form of an elongated cleat secured by bolts 14 to the rack bottom and having a raised outer end 15 pro-

vided with a square opening 16 through its raised portion, the outer end of the latter being flush with or if desired, spaced inwardly from the outer edge of the rack bottom. The other bracket of said pair 70 consists of a cleat 17 secured in a vertical position by bolts 18 to one of the sides. The lower end 19 of this vertical bracket is adapted to seat on the raised end portion 15 of the horizontal bracket and is shaped 75

to provide a hooked tongue 21, adapted to pass through the opening 16 and engage beneath said bracket portion 15. It will be observed that the bottom portion 19 seats on the horizontal bracket at the outer side 85 of the opening 16, and that the tongue hooks under said bottom bracket at the inner side of said opening, thereby effectually supporting the rack sides and locking them against outward movement. It will be fur- 90

ther observed that the uprights 11 are positioned in alignment with the cross beams 7 and that their lower ends have a thrust engagement against the outer ends of said beams, thereby further insuring substantial 95 support of the sides under heavy loads. The sides may be quickly removed, simply by swinging their upper ends inwardly, whereby to withdraw the tongues 21 from the openings or sockets on the bottom brackets. 100

Braces are provided for holding the sides in upright position and against swinging inwardly when the rack is unloaded; these braces being applied preferably to the end brackets only. Each brace comprises a rod 105 22 having a hooked end 23 adapted to engage in the eye lug 24 formed integral with the bracket 17 and provided at its lower end with a laterally projecting pin 25 adapted to pass through the opening in the eye lug 26 formed integral with the bracket 13. Means is now provided for locking the

brace in this position and for permitting quick removal of the brace. This consists in the present instance of a locking member 27 pivotally connected at 28 to the rod and 5 having an opening 29 in its lower end, whereby this end may be snapped over the projecting end of the pin 25. A ring 31 embracing the rod 22 and member 27 is adapted to be slid downwardly thereon to 10 lock the member 27 in holding position.

It will be manifest that the foregoing construction provides a simple and durable means for connecting the sides to a rack bottom, and whereby the sides may be 15 quickly removed when not in use or when the rack bottom is to be used for other purposes. Removal of the sides is effected simply by sliding the links 31 upward sufficiently to permit the locking members 27 20 to be released from the pins 25, whereupon said pins may be withdrawn laterally from the lugs 26, permitting the sides 11 to be swung inwardly and withdrawn from the bottom brackets. It will also be evident 25 that these pairs of brackets and the braces may be easily applied to any rack, and that by reason of their simple construction they may be produced at a comparatively low cost.

30 It is believed that the foregoing conveys a clear understanding of the objects prefaced above, and while I have illustrated but a single working embodiment, it should be understood that changes might be made in 35 details of construction without departing from the spirit and scope of the invention as expressed in the appended claims, in which:

I claim:

1. A pair of brackets for detachably connecting a wagon side to the bottom, comprising an elongated horizontal bracket adapted 40 to be bolted to said bottom crosswise thereof, said bracket having a vertical opening in its outer end, and an elongated upright 45 bracket adapted to be bolted to said side and terminating at its lower end in a hooked tongue adapted to be passed through said opening in the horizontal bracket, said hooked tongue adapted to engage beneath 50 the horizontal bracket at the inner side of said opening and the upright bracket being shaped at its lower end to seat on said horizontal bracket at the outer side of said opening, whereby to detachably support said side 55 in upright position on said bottom, and whereby said connection between the brackets carries outward strains imposed on said side.

2. A pair of brackets adapted for detachably connecting an upright wagon side to the bottom, comprising an elongated horizontal bracket adapted to be bolted to said bottom and having a raised outer end provided with a vertical opening therethrough, a vertical bracket adapted to be bolted to 60 said side and terminating at its lower end in a hooked tongue adapted to pass through said opening and to engage beneath the raised portion of the horizontal bracket at the inner side of said opening, said bracket 65 adapted to seat at its lower end on said raised outer end of the horizontal bracket at the outer side of said opening.

3. A pair of brackets for detachably connecting a wagon side to the bottom, comprising an elongated horizontal bracket adapted to be bolted to said bottom crosswise thereof, said bracket having a vertical opening in its outer end, an elongated bracket adapted to be bolted to said side 75 and terminating at its lower end in a hooked tongue adapted to be passed through said opening in the horizontal bracket, said hooked tongue adapted to engage beneath the horizontal bracket at the inner side of 80 said opening and the upright bracket being shaped at its lower end to seat on said horizontal bracket at the outer side of said opening, whereby to detachably support said side in upright position on said bottom, and whereby said connection between the brackets carries outward strains imposed on said side, an upstanding lug on the inner end of 85 said horizontal bracket, an inwardly projecting lug on the inner end of said vertical bracket, and a brace adapted to be connected to and interposed between said lugs for preventing said side from swinging inwardly 95 at its upper end.

4. A rack structure of the character described comprising crossbeams, flooring thereon, brackets bolted to the top of said flooring and having raised outer ends each provided with a socket opening, sides composed of uprights and horizontal boards secured to the outer edges thereof, brackets bolted to the inner sides of said uprights and adapted to seat on the outer ends of 100 said bottom brackets and each having a depending inwardly turned tongue adapted to enter the opening in its respective bottom bracket, said uprights having lower ends 105 adapted to have thrust engagement with the rack bottom, and braces connecting the sides in upright position.

SAMUEL J. HORSCH.
